US0D1075655S

(12) **United States Design Patent** (10) **Patent No.:** **US D1,075,655 S**
(45) **Date of Patent:** **** May 20, 2025**

(54) **BATTERY CHARGER**

(71) Applicant: **Delta-Q Technologies Corp.**, Burnaby (CA)

(72) Inventors: **Johannes Cornelis Bos**, Cloverdale (CA); **Vincent Pierre Beauvais**, Port Coquitlam (CA); **Jonathan Eric Stroud**, Surrey (CA)

(73) Assignee: **Delta-Q Technologies Corp.**, Burnaby (CA)

(**) Term: **15 Years**

(21) Appl. No.: **29/913,457**

(22) Filed: **Oct. 2, 2023**

(57) **CLAIM**

The ornamental design for a battery charger as shown and described.

DESCRIPTION

FIG. 1 is a top, left, front isometric view of a battery charger of our new design.

FIG. 2 is a bottom, right, rear isometric view thereof.

FIG. 3 is a top, left, rear isometric view thereof.

FIG. 4 is a bottom, right, front isometric view thereof.

FIG. 5 is a top plan view thereof.

FIG. 6 is a bottom plan view thereof.

FIG. 7 is a front elevation view thereof.

FIG. 8 is a rear elevation view thereof.

FIG. 9 is a right side elevation view thereof; and,

FIG. 10 is a left side elevation view thereof.

The broken lines in the figures represent portions of the article which form no part of the claimed design.
